KEY GENERATOR
Lynn W. Marsh, Jr., Marblehead, Mass. (300 Park Terrace Drive, Apt. 337, Melrose, Mass. 02176)
Filed Mar. 5, 1954, Ser. No. 414,521
3 Claims. (Cl. 35—4)

This invention is in cryptologic apparatus and particularly is a novel means for generating a keying sequence.

In many forms of communications, such as teletypewriter, the intelligence signal before transmission is reduced to a sequence of mark-space bauds, which bauds may be represented by on-off signals or by signals of any two convenient values.

Encipherment of a mark-space sequence is commonly accomplished according to the so-called Vernam rule, explained at length in the United States patent to Vernam, No. 1,310,719, which may briefly be said to mean that, whenever two marks occur simultaneously (one in an intelligence signal and the other in a keying signal), a mark is transmitted and, whenever two spaces occur, a mark likewise is transmitted, whereas when two dissimilar signals occur, a space signal is transmitted. The rule is capable, of course, of variation.

The foregoing is merely to illustrate that in present day cryptographic operations large amounts of key, comprising sequences of mark-space values, are necessary and further that security in such operations depends almost entirely upon the unpredictability of the order of the mark-space values of the keying sequences; the requirement of unpredictability is not met necessarily by randomicity, since a random order may include a long succession of mark signals "balanced out" by a preponderance of space signals later.

The principal object of this invention is to provide means for generating a very long unpredictable keying sequence.

Another object is to provide a fast light-operated key generator.

A further object is to provide a novel key generator utilizing a light source, a plurality of light paths, a light sensitive cell, and means for interrupting the paths between the source and the cell at virtually unpredictable intervals.

Other objects will be apparent from a reading of the following specification and claims.

In the drawings:

FIGURE 1 is an illustration, somewhat diagrammatic, of the principal features of my invention; and

FIGURE 2 is an elevation of a light-chopping disc utilized in the invention.

Referring to the drawings and particularly to FIGURE 1, 10 is a motor which drives a shaft 11 whereon are mounted pinions 12, 13, 14, and 15 which mesh with teeth on the peripheries of discs 12', 13', 14', and 15', respectively. As shown, the discs are regularly spaced but, as will hereinafter appear, this arrangement is not essential.

It will be observed that discs 12', 13', 14', and 15' are of different sizes. They are, however, in the preferred embodiment of the invention, rotated at the same peripheral speed, that is, at the same number of teeth per second. The arrangement illustrated, therefore, which includes a separate shaft (12a, 13a, 14a, and 15a, only a fragment of each being shown) for each wheel, is a simple solution to the problem although, obviously, by modification of driving means 11, 12, 13, 14, and 15 the same result can be achieved with a single straight shaft. It will be understood, of course, that in the construction shown the shafts 12a, 13a, 14a, and 15a do not rotate, but instead the wheels rotate upon the shafts, and some means, as collars

2

12₁—12₂, 13₁—13₂, etc., should, therefore, be provided to prevent slipping of the discs lengthwise upon the shaft.

As can be seen from the drawings and especially FIGURE 2, wheel 12' (which is representative of wheels 13', 14', and 15') is relatively thin, with peripheral teeth 23 for cooperation with the teeth of pinion 12, and opening 24 adapted to fit over shaft 12a of FIGURE 1. The disc is made of any convenient opaque material. A 10 ranged in a circular orbit about the center of the disc at any desired distance therefrom is a series of openings 25, there being in the preferred form of the invention one opening for each tooth 23. A second row of openings 26 radially aligned with openings 25 also is provided.

It will be noticed that certain of the openings, as 27 are plugged. Of course, it is not necessary that a full complement of openings be provided in the first place but certain advantages of flexibility are achieved by forming all the holes and providing plugs therefor. As will be explained more fully in the description to follow, the essential security, that is, the degree to which the output of the apparatus is unpredictable, is dependent upon the manner of plugging of the openings in the discs, and the selection of openings to be plugged may, therefore, mathematically computed rather than random. Furthermore, in order to lengthen the cycle of the apparatus, the wheels will be provided with as large numbers of teeth and openings as practicable, and the numbers in the respective wheels will preferably be prime each to the others.

Referring further to FIGURE 1, there may be seen four lamps 30, 31, 32, and 33. They are normally lighted and supply input signals for the key generator. Extending from light source 30 to a point adjacent disc 12' is a rod 40 of Lucite or other material exhibiting a high degree of photoconductivity. The rod is aligned opposite a position in a row of openings in disc 12'; a similar rod extends from the same position in the same row of openings in disc 12 to some position in some row of openings in wheel 13'. Further Lucite sections 42, 43, and 44 complete a light path through the system of discs. Similar paths are provided for each of the other light sources 31, 32, and 33, these terminating respectively at 45, 46, and 47.

Just beyond the output ends 44, 45, 46, and 47 of the several Lucite paths are arranged a lens 50 and a photocell 51. No means are shown for utilizing the output of the photocell, but it may be amplified and used to control any of a number of circuits, the ultimate action which will be in the preferred embodiment of the invention to generate a sequence of on-off signals; an on signal for example, when cell 51 receives some light and an off signal when cell 51 receives no light, the cell being sensitive only to conditions of light and no light.

While four light paths are shown, the number is not critical, and either more or fewer can be used, and, of course, the discs can be provided with three or four rows of openings as easily as two. Still further, a single light source can be used in place of light sources 30, 31, 32, and 33 just as a single photocell 51 is utilized for the output of the apparatus.

With the parts assembled as in FIGURE 1 and discs 12' through 15' rotating under the influence of motor 10 at some speed determined by the desired characteristics of the keying signal, the several lamps 30, 31, 32, 33 and their respective light paths will cooperate with the openings of the several discs 12' through 15' to provide the photocell 51 with intervals of light separated in virtual unpredictable order by intervals of no light.

The foregoing description is in specific terms, and many modifications will suggest themselves. For the true scope of the invention, therefore, reference should be had to the subjoined claims wherein it may be noted the expressio

normally interrupted" may be used for convenience to e the paths from the light source to the photocell though obviously such paths can be properly considered "normally" complete.

Claim:

A key generator including a light source, a light sensing device, a normally interrupted path for light from source to said device, a plurality of discs having openings therein, said openings completing said path when said discs are in predetermined disc-to-disc relation, and means for rotating said discs simultaneously.

A key generator including a light source, a light sensing device, a plurality of normally interrupted paths light from said source to said device, a plurality of discs having openings therein, said openings being adapted to complete a path when in predetermined disc-to-disc relation, and means for simultaneously rotating said discs thereby to change the disc-to-disc relations of said discs.

In a key generator, a disc of opaque material having an annular array of openings therethrough, another disc of opaque material having an annular array of a different

number of openings therethrough, means for selectively obscuring said openings, means for rotating the discs simultaneously at different rates so that the openings progress at the same rate, a plurality of paths of photoconductive material between said discs each of said paths terminating adjacent but spaced from a disc and aligned with an opening therethrough, means for introducing light to said paths, and a photosensitive device positioned to be exposed to light emerging from said paths.
